(57) CLAIM

The ornamental design for a brush head as shown and described.

DESCRIPTION

FIG. 1 is a front perspective view of a brush head showing my new design;

FIG. 2 is a bottom, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the brush head in an environment of use; and,

FIG. 10 is an enlarged view of portion 10 shown in FIG. 1. The dash-dash broken lines immediately adjacent to the shaded areas depict the bounds of the claimed design, while all other dash-dash broken lines are directed to environment. The broken lines form no part of the claimed design.

The dot-dash broken lines represent the boundary of the enlarged portion and form no part of the claimed design.
